UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

1,337,116.

Specification of Letters Patent.

Patented Apr. 13, 1920.

Application filed October 26, 1918. Serial No. 259,800.

To all whom it may concern:

Be it known that I, FRED S. CARR, a citizen of the United States, and resident of Newton, in the county of Middlesex, Commonwealth of Massachusetts, (whose post-office address is care of Carr Fastener Company, Cambridge, Massachusetts,) have invented an Improvement in Fasteners, of which the following description, in connection with the accompanying drawings, is a specification, like characters on the drawings representing like parts.

This invention relates to improvements in separable fasteners, and more particularly, though not exclusively, to improvements in separable fasteners wherein a stud having an expansible head co-operates with a socket having a stud-engaging portion of fixed dimensions, and wherein the stud is separable from the socket by tipping movement in one direction only.

This application is in part a renewal or continuation of and in part a substitute for my application Serial No. 204,252, filed November 27, 1917, and allowed April 5, 1918.

In the drawings:—

Figure 1 is a front elevation of a preferred form of one embodiment of my invention;

Fig. 2 is a section thereof on the line 2—2 of Fig. 1;

Fig. 3 is a rear elevation of the embodiment of my invention shown in Fig. 1;

Fig. 4 is a top view of a preferred form of resilient jaw for use in connection with my invention; and

Fig. 5 is a side elevation of the jaw shown in Fig. 4.

In the preferred form of my invention selected for illustrative purposes, I have shown a socket in the form of a round hole in the side 6 of an automobile. I have shown a stud secured to an automobile curtain 7 and having a head 8, preferably pressed from a flat plate of metal, and providing on one side thereof an abrupt shoulder 9 for engagement with the side of the socket, and preferably being provided on the opposite side thereof with a resilient expandable element 10 projecting through a slot 11 in the side of the head 8 of the stud, and preferably formed of wire crimped between the base flange 12, the head of the stud and a flange 13, from which there projects a tubular portion 14 adapted to be ex-

panded over and engage a clench plate 15 on the opposite side of the curtain 7, thereby to secure the stud firmly to the curtain and to provide an advantageous form of fastening for the resilient jaw element.

The jaw element 10 preferably has its outer end contained within the head 8 of the stud in such a way that the looped portion thereof, adapted to engage the opposite side of the socket aperture from the non-resilient abrupt shoulder 9, may resiliently engage the opposite side of the aperture in the socket.

When it is desired to enter the stud in the socket, the head of the stud is pressed against the aperture in the socket and the resilient element 10 recedes into the head of the stud, thereby permitting the head of the stud to enter the socket, and as soon as the shoulder 9 has passed the inner edge of the socket the spring element 10 will push the head upwardly so that the fixed jaw 9 firmly engages the inside of the socket. At the same time the rounded portion of the spring jaw 10 preferably overlies the opposite side of the aperture in the socket, resisting to some extent any minor forces exerted to remove the stud from the socket. The base flange 12 and the flange 13 are preferably, as shown, extended downwardly away from the shoulder 9 to a greater extent than they extend upwardly toward the shoulder 9 so that the base flange 12 can lie closely against the front of the socket without interfering with tipping movement of the stud relative to the socket when it is desired to remove the stud from the socket. The latter operation is very easily performed by grasping the edge of the curtain 7 below the stud and giving it a sharp outward and upward pull which causes the stud to rock about the shoulder 9, compressing the resilient jaw 10, until the stud can be removed from the socket by an unbuttoning action which permits the shoulder 9 to slip out of the socket.

The present disclosure differs from that of Serial No. 204,252 in that the stud is proportioned substantially to fill the socket at the top and bottom so that any upward strain on the curtain is taken directly on the unyielding portion of the stud and socket instead of on the spring, the latter serving to press and hold the stud and socket relatively in engaged position.

While I have shown and described one

embodiment of my invention, it will be understood that changes involving omission, alteration, substitution and reversal of parts, and even changes in the mode of operation, may be made without departing from the scope of my invention, which is best defined in the following claims.

Claims:

1. A stud and socket fastener comprising, in combination, a socket having an aperture therein, and a stud having a shell providing a fixed abrupt shoulder for engagement with one side of the aperture in the socket, an aperture in said shell and a rounded resilient element projecting through said aperture for engagement with the opposite side of the aperture in said socket, said resilient element pressing said abrupt shoulder into engagement with the opposite side of said socket. 5
2. A stud and socket fastener comprising, in combination, a socket having an aperture therein, and a stud having a head and a neck, one side of said neck providing an abrupt shoulder for engagement with the socket, said head having a slot therein and a resilient jaw element extending through said slot for engagement with the opposite side of the aperture in the socket from said abrupt shoulder. 10
3. A stud and socket fastener comprising, in combination, a socket, a stud for engagement with said socket separable from said socket by tipping movement in one direction only, said stud having a shell providing an unyielding relatively abrupt socket-engaging portion at one side thereof and carrying a yielding rounded socket-engaging element projecting through an aperture therein for holding said unyielding shoulder in engagement with the socket. 15
4. A stud and socket fastener comprising, in combination, a socket having an aperture therein, and a stud having a shell presenting an unyielding socket-engaging element at one side thereof and a yielding socket-engaging element at an opposed portion thereof, said yielding socket-engaging element being formed of a piece of wire bent around the base flange of said stud. 20
5. A stud and socket fastener comprising, in combination, a socket having a substantially round aperture therein, said aperture having unyielding walls, and a stud for entrance in said aperture and engaging said socket, said stud comprising a shell separable from said socket by tipping movement in one direction only, and presenting a yielding socket-engaging element yieldingly opposing separation of said stud and socket by tipping movement in that one direction. 25
6. A stud and socket fastener comprising, in combination, a socket having an aperture therein, and a stud having a shell providing a fixed relatively abrupt shoulder for engagement with one side of the aperture in the socket, an aperture in said shell and a rounded resilient element projecting through said aperture for engagement with the opposite side of the aperture in said socket, 70 said resilient element pressing said relatively abrupt shoulder into engagement with the opposite side of said socket. 75
7. A stud and socket fastener comprising, in combination, an apertured socket and a stud having a head provided at one side with a substantially rigid shoulder for engagement with the margin of the aperture and having a slot opposite said shoulder, an element projecting through the slot and providing a shoulder for engagement with the margin of the aperture, said element being resiliently mounted for inward yielding when pressed radially against said margin, one of said shoulders being abrupt and the other inclined. 80
8. A stud and socket fastener comprising, in combination, a socket providing an aperture having unyielding walls, a stud for engagement therewith having a body portion providing an unyielding relatively abrupt shoulder for engagement with one side of the aperture in the socket, an unyielding neck portion opposite said abrupt shoulder and substantially filling the aperture, and a sloping resilient element carried by said body portion holding said stud and socket in engaged relationship, said stud and socket being separable by relative tipping movement in one direction only. 90 95
9. A stud and socket fastener comprising, in combination, a socket having an aperture therein and a stud providing an inexpansible body portion having at one side thereof an abrupt shoulder and a neck portion behind said shoulder substantially of the same dimension longitudinally as the corresponding dimension of the aperture in the socket, a spring carried by the body portion of the stud and pressing against said socket to hold the same in engaged relation to the stud, said spring being yieldable to permit withdrawal of the stud from the side of the socket opposite the abrupt shoulder on the stud. 100 105 110 115
10. A separable fastener comprising, in combination, a socket, and a stud having an expansible head, said stud and socket separable by relative tipping movement in one direction only, said stud presenting for direct engagement with said socket a neck portion unyielding in all directions co-planar with the plane of the socket, and yielding means on the stud for detachably maintaining said stud and socket in engaged relation. 120 125
11. A fastener comprising, in combination, a socket and a stud having a body portion providing at one side thereof a projection behind which one side of the socket may engage, said stud having at the opposite 130

side thereof a wall for engagement with the other side of the socket, said wall continued outwardly and sloping toward the axis of the stud from the adjacent joint of engagement between the socket and the neck of the stud, said stud snugly fitting the aperture in the socket and resiliently retained therein.

12. A fastener comprising, in combination, a socket and a stud having a body portion providing at one side thereof a projection behind which one side of the socket aperture may engage, said stud having at the opposite side thereof a wall for engagement with the other side of the socket aperture,

ture, the distance from the surface of the 15 stud rearwardly of said projection to all points on said opposite wall being less than the diameter of the aperture in the socket and the distance from the top of said projection to the portion of said wall normally 20 engaged by the socket being greater than the diameter of the aperture in the socket, said stud resiliently opposing separation thereof from said socket.

In testimony whereof, I have signed my 25 name to this specification.

FRED S. CARR.

It is hereby certified that in Letters Patent No. 1,337,116, granted April 13, 1920, upon the application of Fred S. Carr, of Newton, Massachusetts, for an improvement in "Fasteners," an error appears in the printed specification requiring correction as follows: Page 3, line 4, claim 11, for the word "joint" read *point*; and that the said Letters Patent should be read with this correction therein that the same may conform to the record of the case in the Patent Office.

Signed and sealed this 11th day of May, A. D., 1920.

[SEAL.]

M. H. COULSTON,

Acting Commissioner of Patents.
